UNITED STATES PATENT OFFICE.

ALFRED GASKILL, OF PHILADELPHIA, PENNSYLVANIA, ASSIGNOR TO WHIT-
ALL, TATUM & CO., OF SAME PLACE AND NEW YORK, N. Y.

DESIGN FOR A BOTTLE-CAP.

SPECIFICATION forming part of Design No. 24,334, dated May 28, 1895.

Application filed November 12, 1894. Serial No. 527,980. Term of patent 14 years.

To all whom it may concern:

Be it known that I, ALFRED GASKILL a citizen of the United States, residing in Philadelphia, Pennsylvania, have invented a new and original Design for a Bottle-Cap, of which the following is a specification.

My design for a bottle cap is fully shown in the accompanying drawings, in which—

Figure 1 represents a side view of said bottle-cap, and Fig. 2 a plan view of the same.

The cap is of cylindrical form and has at the bottom a plain band *a*, immediately above which is a projecting rounded rib *b* and above the latter a tapering or concave band *d*. Above the band is a tapering and vertically

ribbed portion *f* the ribs being convex and gradually flaring at the base to accord with the increased diameter of the cap at that point due to the tapering form of the same.

I claim—

The design for a bottle cap, substantially as described and shown.

In testimony whereof I have signed my name to this specification in the presence of two subscribing witnesses.

ALFRED GASKILL.
